UNITED STATES PATENT OFFICE.

WILLIAM HENRY GREGORY GEAKE, OF KILLARA, SYDNEY, AUSTRALIA, ASSIGNOR TO
WALTER RUTHERFORD, OF LONDON, ENGLAND, AND JOHN BAIN, OF OTTAWA,
CANADA.

COMBINED CONTAINER AND GREASE GUN.

Application filed February 4, 1926. Serial No. 35,826.

This invention relates to a combined container and grease gun, and has for its object the production of a simple and efficient container and dispensing mechanism whereby semi-fluid materials such as pastes, creams, gums, greases, ointments, powders, and the like, are stored and dispensed as and when required.

Another object includes the production of a construction which will fully protect the material but which affords ready means for dispensing said material with ease, and certainty, in controlled quantities.

A further object includes the provision of a simple and efficient dispensing container which protects the materials against loss and deterioration through exposure, oxidation and evaporation. I further provide a container of the type specified, which is provided with effective control parts in the form of a movable bottom portion, which cooperates with an adjustable discharging device and means for varying the relative distances of said parts from the discharging end of the container, and from each other.

Other objects will appear hereinafter, and I attain these objects by the construction illustrated by the accompanying drawing, in which

Fig. 1 is a plan view of a construction which embodies the principles of my invention.

Fig. 2 is a plan view of a slightly different form of construction from that disclosed in Fig. 1.

Fig. 3 is a section taken on the line 3—3 of Fig. 1.

Fig. 4 is a section taken on the line 4—4 of Fig. 2.

Fig. 5 is a view in section of a modified form of adjustable discharge device or plunger with its control stem.

Like numerals refer to similar parts throughout the several views wherever they occur.

It is among the prime purposes of my invention to produce a simple and inexpensive dispensing container which comprises a main body part, of cylindrical or other shape, closed at one end, and provided with a movable cap and control device at the other. The dispensing container, in its simplest form, comprises a body 10, which is open at one (the lower) end 11, and at its other end

is sealed with a cover 12, having a dispensing nozzle 13, or 13', of suitable diameter, and fitted with a cap 14, or the like. The dispensing opening or nozzle, may be of any desired size, and it may be variously situated or shaped. For some purposes I provide said opening at or near the periphery, and the said nozzle may be curved, as in Fig. 3, for example, for convenience in dispensing the ointment, cream, grease, or other material. In Fig. 4, the opening is located centrally, and in either case, the screw cap 14 fully protects the contents of the container.

The open, or operative end 11 of the main body part 10 is provided with a control cap or thimble 16, or 16', which slidably fits on the main body part.

In Fig. 3, this cap fits over the end of the container body, while in the construction of Fig. 4, said cap 16' fits within the container. In either case this cap is reciprocably held, and is provided with means for dispensing the contents of the container. This dispensing means, in a preferred construction, consists of an adjustable piston or plunger 17 (or 17') having a sealing member 18 (or 18') to form a slidably non-leak connection with the inner walls of the container. This piston or plunger will be shown herein as the adjustable dispensing member, and has a centrally placed screw threaded bore through which operates the adjusting stem or member 20 (or 20') for compressing the material within the container to thus cause the desired amount to be extruded from the nozzle after the cap, 14, has been removed. The compression or moving force is effected by merely pressing the cap and the container body together the necessary distance, thereby causing the dispensing member or plunger to be moved upwardly, that is, towards the dispensing nozzle. When the thimble has been moved forward, to say the end of its movable distance, or a portion thereof, it is readjusted, or caused to be withdrawn for future use. This readjustment is effected by rotating the screw-stem so as to readjust the thimble, that is, cause it to be again moved away from the end 11 for future use. If the adjusting stem is secured to the bottom of the thimble, as in Figs. 3 and 4, for example, then will the readjustment be made by merely turning the cap to unscrew the stem.

100
105

If, on the other hand, the container and thimble are of other shape than cylindrical, as for example, polygonal, or oval, or other form, then will the stem have to be rotated independently of the cap for readjustment. This may be effected in numerous ways, as by keeping the foot 22 of the stem unsecured at the bottom of the thimble, so that the stem can be unscrewed. In such construction, to keep the cap or thimble from falling off, I provide a frictional connection between the body and thimble, and the thimble or cap frictionally engages the side walls of the body member, either externally, or internally. For some purposes, I provide the connecting joint ends of the body and the thimble, respectively, with stop rings 31 and 31'. The stem may be cut screw-threaded, as is shown in Figs. 3 and 5, for example, or it may be a simple coiled corkscrew type of stem. If desired, a stop nut 32 may be provided. The sealing medium 18 or 18' may be leather, composition material, gum, wax, or the like, to make a tight joint.

The operation of my device is very simple and effective. If material is to be dispensed, the cap is removed and a slight pressure given to the container before lifting it from the table or shelf to extrude the desired quantity, or the thimble is pressed while the container is properly held, so as to supply the ointment, grease, or cream to the desired place. This pressure acting through the stem also causes the plunger to rotatively advance thereon to force material from the nozzle. When the cap, and of course, the plunger, have advanced so that the edge of the container engages the bottom of the cap, a readjustment of the stem is necessary. This readjustment is accomplished in the manner stated, by giving the cap and stem (or the stem only) a few turns, as will readily be understood. The plunger or adjustable distributing member is gradually advanced to its extreme position in the top of the container. Usually the plunger is advanced but once. If, however, the container is to be refilled, this may be readily accomplished by withdrawing the cup and attached parts, including the piston member, and refilling the container by supplying the semi-fluid material. In case a powdery material is used, as tooth or soap powder, the container is preferably refilled by supplying the material in bags or charges, which are

used as required. The bag may be paper or other material, and the entire charge and bag may be placed into the container, with the end towards the nozzle open.

Having now described my invention, what I claim as new and useful, and desire to secure by Letters Patent, is:

1. In a dispensing container for semi-fluids, powders and like materials, the combination of a body part open at one end and having a discharge nozzle, an operating member slidably engaging the walls of said body part, a dispensing member in said body part, and means for varying the relative distance between the dispensing member and the bottom of the operating member to effect ejection of the contained material from the body part.

2. In a dispensing container for semi-fluids, powders and like materials, the combination of a body part open at one end and having a discharge nozzle, an operating member engaging the walls of said body part, a piston in the body part arranged to close the open end for pressing on the contained material, a screw threaded stem extending from the operating member and adjustably engaging the piston for varying the distance between the bottom of the operating member and the piston.

3. In a dispensing container for semi-fluids, powders and like materials, the combination of a body part having an open end and a closed end, said closed end being provided with a nozzle, an operating member fitting the open end, a stem resting on the bottom of the operating member and extending into the body part, and a dispensing member operatively carried on said stem and adapted to be moved toward the nozzle when the operating member is made to telescope with the body part.

4. A dispensing container having a nozzle and an open end, a movable bottom in said open end, means for pushing said bottom towards the nozzle comprising a thimble slidably engaging the container at said open end and a connection between said movable bottom and said thimble whereby said bottom means is positively advanced by pushing on said thimble.

In testimony whereof I have hereunto set my hand on this 10th day of November, A. D. 1925.

WILLIAM HENRY GREGORY GEAKE.
